SAMUEL D. POLSEN, OF BRIDGEPORT, CONNECTICUT.

HEADLIGHT.

Application filed March 25, 1928. Serial No. 97,336.

This invention relates to a headlight, and has more particular reference to a headlight equipped with a device for deflecting direct rays of light emanating from a headlight 60 lamp.

An object of the invention is to provide a headlight with deflector which is of simple, novel and improved construction, and is associated with said headlight in a practical, 65 novel, and efficient manner.

A further object is to provide an improved deflector for direct rays of light emanating from a headlight lamp adapted to arrest objectionable direct rays which would otherwise 70 diverge widely directly in front of the headlight.

A further object is to provide a novel deflector, as stated, which will be an article of manufacture adapted to be incorporated in any headlight, and which will include spaced apart deflecting surfaces adapted to be adjacent the headlight lens.

A further object is to provide a deflector, as stated, which will be, in itself, a separate and complete article of manufacture adapted to be incorporated in any headlight, and which will include spaced apart deflecting surfaces of general curved conformation, all of which surfaces are adapted to be approximately perpendicular to a headlight lens.

A further object is to provide a deflector for headlights which will consist of duplicate part-circle units secured to each other 85 in any suitable and convenient manner to produce a deflector of circular conformation.

A further object is to provide a deflector of the character set forth, the parts of which are separate units secured together, each 90 unit consisting of a single strip or piece of suitable material formed to provide spaced apart deflecting surfaces one within the other, each deflecting surface being connected to the next adjacent deflecting surface by a part of said strip or piece.

A further object is to provide a deflector of the character set forth, the parts or halves of which are separate units secured together in some preferred manner, each unit consisting of a single strip or piece of suitable material formed to provide arc shaped, spaced apart deflecting surfaces, one within the other, each arc shaped surface being connected to the next adjacent arc shaped surface by a part of said strip or piece.

A further object is to provide a deflector

as just stated wherein the connections between the arc shaped deflecting surfaces of the different units are all straight and are in alignment, said connections of the different units of the deflector being adapted to be secured to each other at the diameter of the completed deflector in such manner as to provide a continuous strengthening rib across a diameter of said deflector, or along radii of 65 said completed deflector.

A further object is to provide a unique and satisfactory arrangement for securing the diametrical halves of the deflector to each other.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and meant in no way in a limiting sense, changes in details of construction and arrangement of parts being permissible so long as within the spirit of the invention and the scope of the appended claims.

In the accompanying drawing forming a part of this specification,

Fig. 1 is an elevational view of the deflector as it would appear at the front of a headlight, the two halves of the deflector being secured together as by welding or soldering.

Fig. 2 is a similar view of a diametrical half of the deflector of Fig. 1;

Fig. 3 is an elevational view of a modified form of deflector as it would appear at the front of a headlight, the two halves of the deflector being of the same construction as in Fig. 1, but the securing of the halves together being accomplished by a special device;

Fig. 4 is a plan view of a special device 100 adapted to be bent and applied to the deflector to secure the halves thereof together as in Fig. 3;

Fig. 5 is a sectional view on line 5—5 in Fig. 3;

Fig. 6 is a sectional view of a headlight with the deflector incorporated, the disclosure agreeing, generally, with the showing of Fig. 1;

Fig. 7 is a perspective view of an anti-rattling clip to be utilized in the association of the deflector with a headlight; and

Fig. 8 is a perspective view of a strip or piece of material from which the units of the deflector could be constructed, the strip or piece having beads adapted to longitudinally strengthen the material.

With respect to the drawing and the characters and numerals of reference thereon, A is the parabolic reflecting surface of an ordinary headlight, and B is the headlight lamp, C denotes, generally, the deflector of the invention.

Of the deflector, 10 and 11 denote diametrical halves or units each consisting of a single strip or piece of preferably flat metal or other suitable material shaped to form arc shaped, spaced apart deflecting surfaces 12, one within the other, each arc shaped surface 12 being connected to the arc shaped surface adjacent it by a straight connector 13, all of the connectors 13 being in alignment. That is to say, the arc shaped, spaced apart deflecting surfaces 12 are concentric, and the connectors 13 are adapted to practically coincide with the diameter of the finished deflector. Clearly, the deflector could consist of more than two units. Preferably, the connectors of a unit which is less than one-half of a finished deflector would be upon a radius (or radii) of the deflector, as will be apparent.

The halves or units 10 and 11 are desirably duplicates, so that when said halves or units are secured together, they provide a continuous strengthening rib across a diameter of the deflector. See Fig. 1 wherein the connectors 13 are welded or soldered together, each free end of the different halves or units being also welded or soldered to a connector, to thus provide a deflector of circular conformation having a strengthening element 14 directly across its diameter.

In Figs. 3 and 5 the halves or units 10 and 11 are secured together by a special device 15, more clearly illustrated in Fig. 4. The body 16 of this device is of width about equal to the width of the connectors 13, which connectors are preferably the width of the strips or pieces of material from which the deflecting surfaces 12 of the halves or units are made. At the opposite side edges of the body of the device 15 are lugs 17 of width to nicely fit about the connectors 13 of the different halves or units 10 and 11. In the finished deflector, the body 16 of the special device 15 is between the adjacent faces of the connectors 13 of the halves or units 10 and 11, said connectors being in firm engagement with the opposite faces of said body 16, and the lugs 17 are bent about end edges of the connectors, in the manner best disclosed in Figs. 3 and 5, to firmly clamp the halves or units together. The outermost end portions 18 of the body 16 are bent approximately at right-angles to the remainder of the body to engage the

outer faces of the outermost deflecting surfaces of the deflector, and lugs 19 upon said outermost end portions are bent about the opposite side edges of said outermost deflecting surfaces, as will be most clear from Figs. 76 3 and 5. Thus, the special device 15 provides both a means for securing the halves or units 10 and 11 together, as well as a second strengthening element extending diametrically across the deflector.

Both the connectors 13 and the lugs 17 and 19 constitute means insuring the fixed relation of all of the spaced apart deflecting surfaces 12 to each other.

Fig. 6 discloses the manner of application 80 of the deflector to a headlight. The completed deflector, being circular, is adapted to fit nicely against the reflecting surface A, 20 representing anti-rattling clips placed over the inner edges of outermost deflecting 85 surfaces and engaging said reflecting surface A. Each clip 20 preferably consists of shaped metal 21 about which is folded suitable resilient material 22, the ends 23 of the metal being curled or folded back upon 90 the ends of the material 22 to retain it in position. When the deflector is seated against the clips 20, which are themselves seated against the reflecting surface A, the outer edges of the deflecting surfaces 12, or 95 the lugs, 17 and 19, as the case may be, are in position to be engaged by the head light lens D, as indicated at 24, clamped to its customary position in the headlight in any ordinary or preferred manner, so that the 100 reflector A and the lens D insure the position of the deflector in the headlight, as will be very clear from Fig. 6.

When the deflector is situated in a headlight in the manner set forth, the innermost 105 circle thereof, composed of the innermost of the concentric deflecting surfaces 12 of the different halves or units, is adapted to be directly in front of the headlight lamp B, and all of the deflecting surfaces 12 are 110 adapted to be approximately at right-angles to the lens D, between said lens and the lamp. The connectors 13 and the special device 15 offer practically no interference to light passage through the deflector.

In Fig. 8 I have disclosed a strip or piece of material 25 from which the halves or units 10 and 11 of the deflector could be made, said strip or piece of material having longitudinal corrugations or beads 26 adapted to strengthen the strip or piece.

The manner in which the deflector functions is plainly disclosed in dotted lines in Fig. 6. The direct rays of light from the lamp through the innermost circle of the deflector cannot diverge until at considerable distance from the lamp. No direct rays can pass through the other circles of the deflector. All of the reflecting rays passing the circles will be thrown straight ahead with- 125 130

out possibility of divergence close to the headlight. While the deflector offers no noticeable interference to the passage of light from the lamp, it is very effective in arresting objectionable direct rays tending to diverge widely directly in front of the headlight.

Having thus fully described the invention, what I claim as new and desire to secure 10 by Letters Patent is:

1. A head light deflector comprising units each consisting of spaced apart, deflecting surfaces and connectors between said deflecting surfaces, the connectors extending diametrically of the units, and means securing 15 said units to each other in such manner as to provide a brace extending diametrically of said deflector.

2. The combination as specified in claim 20 1, wherein said securing means is a special device between said connectors and having lugs at its opposite side edges bent about the ends of said connectors of the different units.

3. A head light deflector comprising connected part-circle units each consisting of spaced apart, arc shaped, concentric deflecting surfaces and connectors between said deflecting surfaces, the connectors extending diametrically of the units, and the connectors of the different units constituting a continuous brace across the diameter of the deflector.

4. A headlight deflector comprising connected half circle units each consisting of a single strip of material providing spaced apart, arc-shaped, deflecting surfaces and connectors between said surfaces wherein the piece of material has a head extending longitudinally thereof for the purpose described.

5. The combination as specified in claim 3, wherein each unit is composed of a single strip of material.

Signed at Bridgeport, in the county of 45 Fairfield, and State of Connecticut, this 24th day of March A. D., 1926.

SAMUEL D. POLSEN.
